UNITED STATES PATENT OFFICE

**FELIX B. MILLER, OF ATTLEBORO, MASSACHUSETTS, ASSIGNOR TO WILLIAM F. DENNEY,
OF PHILADELPHIA, PENNSYLVANIA**

DESIGN FOR A COMPACT OR SIMILAR ARTICLE

Application filed October 26, 1929. Serial No. 33,176. Term of patent 7 years.

To all whom it may concern:

Be it known that I, FELIX B. MILLER, a citizen of the United States, residing at Attleboro, in the county of Bristol and State of Massachusetts, have invented a new, original, and ornamental Design for a Compact or Similar Article, of which the following is a specification, reference being had to the accompanying drawings, forming a part thereof.

In the drawing showing my new design, Fig. 1 is a perspective view of a compact showing the front, right-hand end, and top thereof;

Fig. 2 is a perspective view of the same, but showing the front, left-hand end, and top thereof;

Fig. 3 is a top plan view;

Fig. 4 is a front elevational view;

Fig. 5 is an elevational view of the left-hand end;

Fig. 6 is an elevational view of the right-hand end;

Fig. 7 is a plan view of the underside of the said compact; and

Fig. 8 is an elevational view of the rear or obverse side of the compact.

The fine vertical lines covering the front side of the compact within the marginal border, as shown in Figs. 1, 2 and 4 of the drawing, indicate a color contrasting to that of the said border and the fine vertical lines covering a similar space on the obverse side of the compact with a similar border, as shown in Fig. 8, indicate stripes of fine vertical grooves cut or imprinted or engraved into the said surface.

I claim:

The ornamental design for a compact or similar article, as shown and described.

FELIX B. MILLER.
